INVENTOR

William O. Myers
By William Attorney

UNITED STATES PATENT OFFICE.

WILLIAM O. MYERS, OF CANTON, OHIO.

BUILDING-BLOCK.

SPECIFICATION forming part of Letters Patent No. 508,577, dated November 14, 1893.

Application filed December 19, 1892. Serial No. 455,566. (No model.)

To all whom it may concern:

Be it known that I, WILLIAM O. MYERS, a citizen of the United States, and a resident of Canton, county of Stark, State of Ohio, have 5 invented a new and useful Improvement in Building-Blocks, of which the following is a full, clear, and exact description, reference being had to the accompanying drawings, making a part of this specification.

10 My invention relates to improvements in building blocks, and consists in providing as a new article of manufacture, a building block molded of plastic clay having means for securing the blocks in vertical order in the wall, and constructed to receive joggles for 15 uniting the ends and closing the transverse vertical opening between the ends of the blocks.

With these ends in view, my invention consists of certain features of construction and combination of parts, as will be hereinafter described and pointed out in the claim.

Figure 1, of the accompanying drawings is a view in perspective of a fragment of a wall 25 showing building blocks illustrating my invention. Fig. 2, is an elevation showing the ends of blocks in vertical order. Fig. 3, is a similar view of end of block, and Fig. 4, is a perspective of joggle.

30 Similar letters of reference indicate corresponding parts in all of the figures of the drawings.

A represents the block which is substantially of the form shown, having at its front 35 an outwardly beveled edge, portions *a*, terminating in an out set panel, *b*. In the lower face of the block is formed a recess or groove *d* adapted to receive the longitudinal rib *e* shown on the upper face of the block, by which 40 the blocks are held in alignment, and in vertical order. It will be noticed that the blocks

are placed so as to break joints, the ribs of blocks *x* and *y*, meeting about central in the groove in block *z* as shown in Fig. 1.

To further secure the blocks in position, 45 that is to prevent the tipping or rocking of the blocks or such movement of a single block, during the construction of the wall or of the blocks composing the top course, and to close the transverse opening between the ends of 50 the blocks, recesses *f* are formed in the end portions of the blocks, as shown in the drawings, into which a joggle piece *B* of the form shown in Fig. 4 is placed, as shown in Fig. 1 by which a back support is formed for the 55 mortar used to form the joint, by which a flow of air through the wall is prevented. This latter or secondary use of the joggle is of great importance, as the side wall of the block is so thin as to form little or no support for 60 the mortar which without the support of the joggle will soon fall out and leave an opening in the wall. To strengthen the block for the purpose of supporting heavy walls, vertical division walls or supports *h* are provided as 65 shown in the drawings, thus dividing the interior of the block into three compartments.

Having thus fully described the nature and object of my invention, what I claim, and desire to secure by Letters Patent, is— 70

As a new article of manufacture, a building block having on its under side a broad central longitudinal recess, on its upper portion a rib corresponding with said recess, and at its ends recesses *f*, substantially as set forth. 75

In testimony whereof I have hereunto set my hand this 14th day of December, A. D. 1892.

WILLIAM O. MYERS.
